Primary Examiner — Richelle G Shelton*(74) Attorney, Agent, or Firm* — Finnegan, Henderson, Farabow, Garrett & Dunner, LLP(57) **CLAIM**

The ornamental design for a display screen with graphical user interface, as shown and described.

DESCRIPTION

The FIGURE is a front view of a display screen with graphical user interface showing the new design.

The broken lines of uneven length showing the display screen and the broken lines of even length are for environmental purposes only and form no part of the claimed design.

1 Claim, 1 Drawing Sheet
